EXPLOSIVE COMPOSITION COMPRISING AMMONIUM NITRATE AND A MIXTURE OF HIGHER BORON HYDRIDES

James S. Logan and Joel A. Zaslowsky, both of Woodbridge, Conn., assignors, by mesne assignments, to Commercial Solvents Corporation, a corporation of Maryland
No Drawing. Filed May 1, 1961, Ser. No. 106,456
3 Claims. (Cl. 149—22)

This invention relates to improved ammonium nitrate explosive compositions and, more particularly, it relates to ammonium nitrate explosive compositions containing yellow solid.

It is an object of this invention to provide ammonium nitrate explosive compositions which upon proper initiation produces a detonation of useful magnitude and force.

Another object of this invention is to provide ammonium nitrate explosive compositions devoid of hazardous components which may be safely handled and transported with little danger of shock initiation and which may be detonated effectively by means of a commercial blasting cap.

Another object of this invention is to provide ammonium nitrate explosive compositions of greatly increased power.

Another object of this invention is to provide ammonium nitrate explosive compositions not dependent upon high explosives or metallic components for their successful functioning.

The pyrolysis of diborane to form higher boron hydrides is well known. The operation can be carried out, for example, at a pressure within the range from 0 to 100 p.s.i.g., at a temperature within the range from 150° C. to 300° C. and with a residence time in the pyrolysis zone of from about 1 second to 6 seconds. The diborane pyrolyzed can be in admixture with diluent hydrogen introduced into the pyrolysis zone along with the diborane, the amount of diluent hydrogen being from about 25 to 95 percent by weight, based upon the weight of the diborane. The pyrolysis of the diborane results in the production of tetraborane, pentaborane-9, pentaborane-11, decaborane and so forth. Note, for example, the article by McCarty and Di Giorgio appearing on pages 3138 to 3143 of the July 1951 issue of the Journal of the American Chemical Society.

Frequently, in diborane pyrolysis a yellow solid is formed in addition to the aforementioned borohydrides. This solid is a mixture of polymerized higher boron hydrides higher than decaborane. The solid can be separated from the decaborane with the aid of kerosene, decaborane being more soluble in kerosene than the yellow solid. This is described, for example, in Zaslowsky and Madaus application Serial No. 560,113, filed January 19, 1956 (now U.S. Patent 2,983,590). The yellow solid is in general chemically inert and resists efforts to convert it into readily useable chemical compounds. Sometimes, over 50 percent of the end product of the diborane pyrolysis consists of the yellow solid. The boron lost in this by-product adds to the cost of the pyrolysis operation and, of course, lowers the yield of the desired borohydrides, chiefly pentaborane-9 and decaborane.

Fertilizer grade as well as explosive grade ammonium nitrate can be used in the composition of this invention. Generally, fertilizer grade ammonium nitrate contains various additives or coatings to inhibit caking and to promote free flowing characteristics of the material. The term ammonium nitrate, as referred to herein, is defined as ammonium nitrate containing up to about 3 percent of various additives which can be wax, diatomaceous earth,

2

chalk, etc., in addition to a moisture content ranging up to about 2.0 percent.

The novel explosive compositions of this invention are prepared by admixing particulate ammonium nitrate with particulate yellow solid. In general, the novel explosive compositions will contain from about 2 to about 22 percent by weight of yellow solid.

The particle size of the ammonium nitrate utilized is not critical, however, ammonium nitrate having a particle size range of from about 8 mesh to about 200 mesh is preferred. In a like manner yellow solid having a particle size of from 8 to about 200 mesh can be utilized in preparing the novel explosive compositions of this invention.

The novel explosive compositions of this invention can be charged directly into a borehole and detonated by means of a commercial blasting cap. If desired, these novel compositions can be packaged in a shell of waterproof material such as plastic film, paper treated with paraffin or other waterproofing materials, or in metal cans.

Results of detonation tests conducted in the field showed that ammonium nitrate-yellow solid explosive compositions are substantially more powerful than conventional ammonium nitrate-hydrocarbon oil explosives when tested under the same conditions.

The following examples illustrate various embodiments of this invention and are to be considered not limitative.

EXAMPLE I

Yellow solid in the amount of 13.8 grams (particle size, 100 percent through 100 mesh) was added to a cylindrical vessel containing 186.2 grams (particle size, 100 percent through 40 mesh) of ammonium nitrate. The vessel and contents were then tumble rolled to provide an intimate mixture of the two ingredients. The explosive composition so prepared contained 6.9 percent yellow solid by weight.

To demonstrate the explosive power of the explosive compositions prepared in this example it was detonated in the field. Detonation was achieved by means of a No. 6 Electric Blasting Cap. The charge as tested was packaged in a cylindrical paper container having a diameter of about 2.5 inches. The container with the charge was placed in a suitable hole in such a manner that the top of the charge in the container was flush with the ground. The blasting cap was placed in the explosive charge through the open top of the container and the composition detonated by closing the firing switch. The magnitude of the resulting detonation was determined by measuring the size of the crater produced. Although it is true that the crater size alone is not indicative of the amount of earth formation that is broken up, it does give an indication of the work potential of the mixture detonated. The result of the firing test is given in Table I.

EXAMPLES II AND III

Two additional explosive compositions, both containing 6.9 percent yellow solid by weight, were prepared in the same manner as described in Example I. The particle size of the ammonium nitrate and the yellow solid was the same as that utilized in Example I. Results of firing tests conducted with the explosive compositions of Examples II and III are reported in Table 1.

EXAMPLES IV-VIII

In order to compare the novel explosive compositions of this invention with conventional ammonium nitrate-hydrocarbon oil explosive compositions a number of compositions of the latter type were prepared by admixing kerosene with ammonium nitrate. Granular ammonium nitrate (particle size, 100 percent through 40 mesh) as well as ammonium nitrate prills (average diameter: 0.060 to 0.070 inch) were used. These compositions were then

3

detonated by means of an Engineer Special Blasting Cap. The compositions of the explosive charges prepared in Examples IV-VIII as well as the results of firing tests conducted with these materials are also recorded in Table 1.

Table 1
FIELD TESTING OF AMMONIUM NITRATE EXPLOSIVE COMPOSITION

Example	Weight (grams)	Explosive Composition			Detonator	Crater Volume (inches)
		Yellow Solid (percent by weight)	Kerosene (percent by weight)	Ammonium Nitrate (percent by weight)		
I	200	6.9	0	1 93.1	No. 6 Electric Blasting Cap.	490
II	200	6.9	0	1 93.1	do	450
III	200	6.9	0	1 93.1	Engineer Special Blasting Cap.	960
IV	193	0	5.5	1 94.5	do	190
V	193	0	5.0	1 95.0	do	300
VI	200	0	5.5	2 94.5	do	570
VII	200	0	5.5	2 94.5	do	510
VIII	200	0	5.5	2 94.5	No. 6 Electric Blasting Cap.	(3)

¹ Granular ammonium nitrate. Particle size—100 percent through 40 mesh.

² Prilled ammonium nitrate. Average diameter—0.060 to 0.070 inch.

³ Explosive composition did not detonate.

EXAMPLES IX-XII

A number of additional ammonium nitrate-yellow solid explosive compositions were prepared and tested for impact sensitivity. A one to two gram sample of each particular explosive composition was prepared. Granular ammonium nitrate and yellow solid (particle size of both ingredients, 100 percent through 40 mesh) were used in all instances. The compositions were mixed by rotating the ingredients in small vials for several minutes.

The impact sensitivity determinations reported in Table 2 which follows were conducted using a drop weight tester. The material to be tested was placed in a sample cup and covered with a thin (0.011 inch) stainless steel disc. This was done to prevent actual contact between the sample and the hammer thus eliminating the necessity of cleaning the hammer after each impact. The sample was placed in the tester, the weight was dropped from a measured height and the effect of impact noted. The weight was raised or lowered to determine the height at which explosion occurred in three out of every six samples tested.

The compositions prepared and the results of the impact sensitivity tests are reported in Table 2 below:

Table 2
IMPACT SENSITIVITY OF AMMONIUM NITRATE-YELLOW
SOLID EXPLOSIVES

Example	Yellow Solids ¹ (percent by weight)	Sample Weight (grams)	Weight Dropped (pounds)	Height Dropped (inches)	Impact Producing Detonation (inch- pounds)
IX	6.50	.050	6	13.55	81.35
X	5.00	.050	7	13.83	96.78
XI	4.00	.050	7	12.50	87.40
XII	3.00	.050	7	13.75	94.15

¹ Balance was ammonium nitrate.

What is claimed is:

1. An explosive composition comprising particulate ammonium nitrate and from about 2 to about 22 percent by weight based on the weight of the said explosive composition of particulate yellow solid, said yellow solid being

5

4

a mixture of boron hydrides higher than decaborane obtained by pyrolyzing diborane at a pressure within the range from 0 to 100 p.s.i.g. at a temperature within the range from 150° C. to 300° C. and with a residence time in the pyrolysis zone of from about 1 second to 6 seconds, whereby products including a mixture of boron hydrides higher than decaborane are formed, and separating the mixture of boron hydrides higher than decaborane from the other pyrolysis products.

2. The explosive composition of claim 1 wherein the particle size of the said ammonium nitrate and of the said yellow solid is from about 8 to about 200 mesh.

3. The explosive composition of claim 1 wherein up to 100 percent of the said particulate ammonium nitrate is of fertilizer grade.
